Primary Examiner—Stacia Cadmus

(74) Attorney, Agent, or Firm—Park & Sutton LLP; John K. Park

(57) **CLAIM**

The ornamental design for a wheel, as shown and described.

DESCRIPTION

FIG. 1 is a perspective view of a wheel showing my new design; and,

FIG. 2 is a front elevational view of FIG. 1.

The broken line showing of environment is for illustrative purposes only and forms no part of the claimed design.
